SLAG-TAPPING FURNACE HAVING A FLOOR
WITH INCLINED EDGESRalph M. Hardgrove, Westfield, N. J., assignor to
Fuller Lehigh Company, Fullerton, Pa., a cor-
poration of DelawareApplication August 13, 1930, Serial No. 475,011
Renewed November 19, 1934

8 Claims. (Cl. 122—235)

This invention relates to a furnace that is especially adapted for burning powdered fuel in which slag from the fuel is permitted to collect upon the floor of the furnace in a molten form 5 and is drawn off at intervals.

In furnaces of this character that have been used heretofore, troubles have arisen when the slag is permitted to freeze and subsequently expand when again heated, with a result that the 10 furnace walls are pushed outwardly. This danger is sometimes caused because when the slag cools and freezes, cracks form in it which subsequently receive more molten slag that hardens therein, thus causing the slag slab to grow and expand 15 by successive heating and cooling.

By the present invention, the danger of the walls of the furnace being forced outwardly is obviated by forming the floor in such a manner that the slag that collects upon the floor has thin 20 edges that would be crushed without pushing the furnace walls out. The major portion of the furnace floor is made substantially level but the edges thereof slope upwardly or edges of the furnace floor merge into the lower portions of 25 walls of the furnace along inclined surfaces. In this way, inclined water cooled surfaces are provided upon which the edges of the slab of slag that may form in the furnace can slide.

The invention will be understood from the 30 description in connection with the accompanying drawings, in which Fig. 1 is a vertical section through an illustrative embodiment of the invention; Fig. 2 is a section along the line 2—2 of Fig. 3, and Fig. 3 is a section along the line 35 3—3 of Fig. 1.

In the drawings, reference character 1 indicates a furnace that is provided with one or more fuel burners 2 through one wall thereof.

The front and rear walls of the furnace are 40 provided with upwardly extending water tubes 3 and the side walls of the furnace are provided with upwardly extending water tubes 4. The lower ends of the tubes 3 and 4 extend into horizontally disposed lower headers 6 and the upper 45 ends of these tubes extend outwardly and into horizontally disposed headers 7. Recirculating tubes 8 are provided on the outside of the furnace between the headers 6 and 7. Tubes 9 extend from the upper headers 7 to the steam space of 50 the water tube boiler that is located above the furnace 1, only the lowest row of tubes 10 of this boiler being indicated on Fig. 1 of the drawings. The lower headers 6 may be connected to the water space of the boiler by pipe connections in 55 the usual manner.

A slag tap opening 11 is provided through a wall of the furnace at a slight elevation above the floor of the furnace. The major portion of the floor of the furnace is made up of refractory material 12 supported on cross supports 13.

The lower ends of the front and rear wall tubes 3 and the lower ends of the water tubes 4 in the wall opposite the slag tap opening 11 are bent inwardly at their lower ends, as indicated at 14, to provide sloping surfaces adjacent three of 10 the edges of the floor of the furnace. The fourth wall is substantially vertical where it contacts with the floor. (See Fig. 2.)

It will thus be seen that the lower ends of the water tubes 14 with the refractory covering 15 thereon, provide inclined surfaces along the edges of the floor. As will be seen by referring to Figure 1, rigid supports are provided at the ends of the water tube sections 14, and resilient supports, here shown as spring supports, are provided intermediate the ends of these tube sections.

Short auxiliary headers 6' are provided at two of the corners of the furnace. A few of the tubes at these corners are bent first inwardly and then 25 outwardly as shown in Fig. 3 at 4' and are connected to these headers in such a manner as to prevent tubes in adjacent walls from overlapping or interfering with each other, as indicated in Figs. 2 and 3 of the drawings. Tubes near these 30 corners are bent successively to greater extents to provide satisfactory cooling means over the entire area of the sloping corner portions of the furnace. The headers 6' are connected to the water circulation system of the boiler in a manner 35 similar to the connection of the headers 6.

During the operation of the furnace, the molten slag from the products of combustion falls to the bottom of the furnace and forms a layer, as indicated at 15. Molten slag can be tapped out 40 through the opening 11 when desired. Since the inclined surfaces are water cooled, slag may harden on these surfaces with thin edges, so that heating and cooling of the slag which causes expansion thereof will not force the furnace walls 45 outwardly as the slag can slide up the inclined surfaces along the edges and the thin edges of the slag will be crushed without displacing the furnace walls.

I claim:

1. In a furnace for burning a slag-forming fuel, a furnace bottom constructed to sustain a pool of molten slag, said furnace bottom comprising a central horizontally extending portion comprehending a major portion of said bottom and edge 55

- portions on at least three sides of the central portion and sloping upwardly from said central portion, said edge portions being subjected to a greater degree of cooling than said central portion.
5. In a furnace for burning a slag-forming fuel, a furnace bottom constructed to sustain a pool of molten slag, said furnace bottom comprising a central horizontally extending portion comprehending a major portion of said bottom and edge portions on at least three sides of the central portion and sloping upwardly from said central portion, and cooling tubes in said edge portions, said edge portions being subjected to a greater degree of cooling than said central portion.
10. In a furnace for burning a slag-forming fuel, walls, a furnace bottom constructed to sustain a pool of molten slag, said furnace bottom comprising a central horizontally extending portion comprehending a major portion of said bottom and edge portions on at least three sides of the central portion and sloping upwardly from said central portion, and cooling tubes in said walls and in said edge portions, each tube extending continuously from the wall into the adjacent edge portion, said edge portions of said floor being subjected to a greater degree of cooling than said central portion.
15. In a furnace for burning a slag-forming fuel, vertically extending side walls having cooling tubes, a furnace bottom comprising a central horizontally extending portion comprehending a major portion of said bottom and inclined margin portions on at least three sides of the central portion, said horizontal portion extending into contact with a vertical portion of one of said
- side walls and a slag tap opening in said side wall.
20. In a furnace for burning a slag-forming fuel, upwardly extending side walls having cooling tubes, a furnace bottom comprising a central horizontally extending portion comprehending a major portion of said bottom, and inclined margin portions on at least three sides of the central portion, the lower ends of said side wall tubes being bent and extended in heat transfer relationship to said margin portion.
25. In a furnace for burning a slag forming fuel, upwardly extending side walls comprising spaced water tubes and closure elements for the spaces, and a furnace bottom comprising a central horizontally extending portion constructed to sustain a pool of molten slag and margin portions on at least three sides of the central portion and inclined to said central portion.
30. In a furnace for burning a slag forming fuel, upwardly extending side walls comprising spaced water tubes and closure elements for the spaces, and a furnace bottom comprising a central horizontally extending portion constructed to sustain a pool of molten slag and margin portions on at least three sides of the central portion and inclined to said central portion and extending above the level of said pool.
35. In a furnace for burning a slag forming fuel, upwardly extending side walls comprising spaced water tubes and closure elements for the spaces, and a furnace bottom comprising a central horizontally extending portion constructed to sustain a pool of molten slag and margin portions on at least two adjacent sides of the central portion and inclined to said central portion.

RALPH M. HARDGROVE.
